PROJECTION KNOB FOR TV CHANNEL SELECTION

James A. Fisher, Metuchen, N. J., assignor to Westinghouse Electric Corporation, East Pittsburgh, Pa., a corporation of Pennsylvania

Application August 26, 1954, Serial No. 452,406

6 Claims. (Cl. 116—124.4)

This invention relates to selector controls, and more particularly to television channel selectors.

It is an object of this invention to provide a selector control with improved means for indicating the position of the control.

It is another object of this invention to provide a television channel selector with improved means for indicating to which channel a television receiver is tuned.

It is a further object to provide a very high frequency-ultra high frequency television channel selector with improved means for indicating to which channel the device is tuned.

These and other objects of the invention are effected as will be apparent from the following description and claims, taken in accordance with the accompanying drawing which forms a part of this application.

In the drawing, there is shown a cutaway side view of a section of a television receiver apparatus including a very high frequency-ultra high frequency channel selector embodying my invention.

Referring to the drawing in detail, a section of a conventional television receiver is shown including a picture tube 10, a picture mask 11, a safety glass member 12, a source of light 13, and a selector control indicated, as a whole, by the reference numeral 14.

The picture tube 10 is enclosed in a cabinet having a front wall 15 and is positioned behind the safety glass member 12. The picture tube 10 rests against a dust seal 16 which extends around the circumference of the forward part of the picture tube 10. One end of the picture tube mask 11 is attached to the dust seal 16, and the other end is attached to the front wall 15 of the cabinet by means of the safety glass member 12. The picture tube mask 11 slopes rearwardly from its position behind the safety glass member 12 and upwardly to the dust seal 16.

The selector control 14 is provided with concentric shafts 17 and 18 which extend through the front wall 15 of the cabinet. The inner shaft 17 is adapted to be connected to certain coil combinations (not shown) which are tuned to the respective very high frequency channels assigned to transmitting stations by the Federal Communications Commission. The outer shaft 18 is adapted to be connected to certain coil combinations (not shown) which are tuned to the respective ultra high frequency channels assigned by the Federal Communications Commission. The fine tuning for both the very high frequency and ultra high frequency channels is accomplished through the shaft 18.

An outer knob 19 is fixed to the inner shaft 17 and controls the movement of the shaft 17. An inner knob 20 is fixed to the outer shaft 18 and controls the movement of the shaft 18. The outer knob 19 has a circular skirt member 21 which is integral with the knob 19 and extends through the front wall 15 of the cabinet. The skirt member 21 has a dial portion 22 which has indicia 23 corresponding to the very high frequency channels imprinted in circumferentially spaced relation on its

2

outer surface. The inner knob 20 is also attached to a circular skirt member 24 which is fixed to a sleeve 25. The sleeve 25 is in turn rotated by the outer shaft 18 to the correct ratio providing a maximum area of skirt member 24 on which to place suitable indicia. The skirt member 24 has a dial portion 26 which has indicia 27 corresponding to the ultra high frequency channels imprinted in circumferentially spaced relation on its outer surface. The dial 26 on the skirt member 24 is substantially in alignment with the dial 22 located on the skirt member 21.

The surface of the dials 22 and 26 are finished in a highly reflective material, such as stainless steel, chromium plate, aluminum, silver and the like, in its metallic state. The indicia 23 and 27 are finished in black so as to reduce light reflection therefrom to a minimum. The dials may have flat, curved or shaped surfaces for indicia to provide clarity or novel effects.

The picture tube mask 11 has a screen portion 28 which is of a translucent material. The light source 13 is mounted under the picture tube mask 11 adjacent to the skirt member 21 and in a position so as to illuminate the surface of the dial 22 when the selector control 14 is operated to tune to a very high frequency channel. When the selector control 14 is operated to tune to an ultra high frequency channel, the light source 13 will illuminate the dial 26 through an opening 29 provided in the dial 22. The light source 13 is preferably as small as possible which can be accomplished by orientation of the filament or by other means known to the art.

In operation, assume the selector control 14 is set to tune the receiver to a very high frequency channel. When the television receiver is connected to operating potentials, the illumination from the light source 13 is cast on the dial 22 which has imprinted on it the numeral corresponding to a particular very high frequency channel. The light cast upon the dial 22 is reflected in such a manner as to project transparent, but easily readable, images on the translucent screen 28. A person may then read the image projected on the screen 28 through the safety glass 12 and ascertain the channel the receiver is tuned to. To tune the receiver to an ultra high frequency channel, the outer knob 19 is turned until the opening 29 provided in the dial 22 is opposite the light source 13. Illumination from the light source 13 is then cast on the dial 26 which has imprinted on it the numeral corresponding to the ultra high frequency channel to which the selector control 14 is turned to. The light cast on the dial 26 is reflected as before to project an image on the screen 28 which is indicative of the ultra high frequency channel to which the receiver is tuned.

As the surfaces of the dials 22 and 26 are finished in a highly reflective material, the indicia projected on the screen 28 appears in dark outline upon a bright background. Of course, the surfaces of the dials 22 and 26 may be finished with a non-reflective material, and the indicia 23 and 27 may be imprinted with a suitable material to reflect a maximum amount of light. In the latter case, the indicia 23 and 27 would appear in bold outline on the screen 28 without any background. Different kinds of color combinations can be obtained by using color lamps or color filters at the light source 13 or at the screen 28. Also, a thin layer of a material of a suitable color may also be placed on the reflective surfaces of the dials 22 and 26 to obtain different color images.

While I have shown my invention in a preferred form, it will be obvious to those skilled in the art that it is not so limited but is susceptible of various changes and modifications without departing from the spirit thereof.

I claim as my invention:

1. In a television channel selector, selector means com-

prising a pair of concentric knobs, one of said knobs having channel indicating means provided with light reflective indicia thereon, a translucent screen disposed adjacent to said channel indicating means, and means to illuminate a portion of said channel indicating means to cause an image of said indicia to be projected onto said translucent screen.

2. In a television channel selector, selector means comprising a pair of concentric knobs, one of said knobs having a circular section extending from the rear of said knob, said circular section having a dial, light reflecting channel indicia provided on said dial, a translucent screen disposed adjacent to said dial, and means to illuminate a part of said dial to cause an image of a single channel indicia to be projected onto said translucent screen.

3. In a television channel selector, selector means having concentric inner and outer shafts, each of said shafts having a knob associated therewith to facilitate turning of said shafts, a first channel indicating means responsive to the turning of said inner shaft with light reflective indicia thereon, a second channel indicating means responsive to the turning of said outer shaft with light reflective indicia thereon, a translucent screen, disposed adjacent to said first and second channel indicating means and means to illuminate separately a portion of said first or said second channel indicating means to cause an image of the indicia thereon to be projected onto said translucent screen.

4. In a television channel selector, a source of light, selector means having concentric inner and outer shafts, each of said shafts having a knob associated therewith to facilitate turning of said shafts, a first channel indicating means responsive to movement of said outer shaft, said first indicating means comprising light reflective indicia, a second channel indicating means responsive to movement of said inner shaft, said second indicating means comprising light reflective indicia, a translucent screen disposed adjacent to said first channel indicating means, said first channel indicating means being positioned between said source of light and said second channel indicating means, said source of light being positioned so as to illuminate separately portions of said first or said second channel indicating means to cause an image of said indicia to be projected onto said translucent screen.

5. In a television channel selector, a translucent screen, selector means having concentric inner and outer shafts, each of said shafts having a knob associated therewith to facilitate turning of said shafts, a first circular member skirting said inner and outer shafts and attached to

said outer shaft, said circular member being provided with a dial with light reflective indicia in circumferentially spaced relation on its outer surface, said light reflective indicia corresponding to one group of television frequency channels, a second circular member skirting said first circular member and integral with the knob associated with said outer shaft, said second circular member being provided with a dial with light reflective indicia in circumferentially spaced relation on its outer surface, said light reflective indicia corresponding to another group of television frequency channels, a translucent screen disposed adjacent to said second circular member, and means to illuminate separately a portion of said dial of said first circular member or a portion of said dial of said second circular member to cause an image of said indicia to be projected onto said translucent screen.

6. In a television channel selector, a translucent screen, selector means having concentric inner and outer shafts, each of said shafts having a knob associated therewith to facilitate turning of said shafts, a first circular member skirting said inner and outer shafts and attached to said outer shaft, said circular member being provided with a first dial with light reflective indicia in circumferentially spaced relation on its outer surface, said light reflective indicia corresponding to ultra high frequency channel designations, a second circular member skirting said first circular member and integral with the knob associated with said outer shaft, said second circular member being provided with a second dial with light reflective indicia in circumferentially spaced relation on its outer surface, said light reflective indicia corresponding to very high frequency channel designations, said second dial being positioned directly over said first dial, a translucent screen disposed adjacent to said second circular member, means to illuminate either a portion of said first dial through an opening provided in said second dial to cause an image of said indicia corresponding to the particular ultra high frequency channel designation to which the selector means may be turned to be projected onto said translucent screen or a portion of said second dial to cause an image of said indicia corresponding to the particular very high frequency channel designation to which the selector means may be turned to be projected onto said translucent screen.
